(57) **CLAIM**

The ornamental design for a holographic image display, as shown and described.

DESCRIPTION

FIG. 1 is a side perspective view of a holographic image display showing my new design.

FIG. 2 is a top perspective view thereof.

FIG. 3 is a side elevational view thereof, each of the other side views being a mirror image thereof.

FIG. 4 is a top plan view thereof; and,

FIG. 5 is a bottom view thereof.

The broken line showing of portions of the holographic image display are for environmental purposes only and form no part of the claimed design.
